CLAIM

The ornamental design for a multi-storied building, as shown and described.

DESCRIPTION

FIG. 1 is a perspective view of a multi-storied building showing my new design,

FIG. 2 is a top plan view thereof, somewhat enlarged,

FIG. 3 is a front elevational view thereof,

FIG. 4 is a side elevational view thereof,

FIG. 5 is a side elevational view thereof, opposite to FIG. 4; and

FIG. 6 is a view in rear elevation thereof.

FIG.1

FIG.3

FIG.2

FIG. 4

FIG. 5

FIG. 6
